Specification of Letters Patent.

Patented Dec. 5, 1916.

Application filed February 2, 1915. Serial No. 5,745.

To all whom it may concern:

Be it known that I, PATRICK H. HICKMAN, a citizen of the United States, residing at Irvington, in the county of Essex and State 5 of New Jersey, have invented certain new and useful Improvements in Lasts, of which the following is a specification.

This invention relates to shoe lasts.

One object is to provide a shoe last particularly adapted for relasting purposes and which embodies toe and heel portions swingingly connected together, one of said portions being expandable and contractible under the influence of the connection between the toe 15 and heel portions.

Another object resides in the provision of a shoe last embodying, among other characteristics, toe and heel portions which have swinging movement relative to each other, 20 with one portion formed to expand and contract when the toe and heel portions are swung in opposite directions relative to each other.

With the above and other objects in view 25 the present invention consists in the combination and arrangement of parts herein-after more fully described, illustrated in the accompanying drawings, and particularly pointed out in the appended claim, it being 30 understood that changes may be made in the shape, size, materials, proportions and minor details without departing from the spirit of the invention or sacrificing any of the advantages of the invention.

35 In the drawings:—Figure 1 is a view, partly in elevation and partly in section, illustrating the last expanded. Fig 2 is a similar view, illustrating the last contracted. Fig. 3 is a detail view of the connecting plate. Fig. 4 is an edge view of the connecting plate. Fig. 5 is a detail view of the sleeve to which the plate is pivotally connected. Fig. 6 is an end view of the sleeve. Fig. 7 is a detail view of the link connection 40 between the plate and the expandable part of the toe portion. Fig. 8 is an edge view of the link. Fig. 9 is a detail view of the spring by which the sleeve is yieldably mounted.

45 Referring more particularly to the accompanying drawings, the reference characters 10 and 11 indicate the toe and heel portions, respectively. The toe portion is preferably slotted, as indicated at 12, to provide the toe 50 portion with an expandable and contractible

section 13. A socket 14 is formed in the heel portion, which is adapted to coincide with the socket 15 formed in the toe portion, there being a recess 16 formed in the expandable and contractible toe portion 13 80 for a purpose presently explained.

The toe and heel portions are swingingly connected together in a manner to be later explained, they meeting along the curved line 17. The heel portion is limited in its upward swing relative to the toe portion by the shoulders 18 and 19 respectively. The heel portion preferably has a socket 20 adapted to take a sleeve 21 designed to receive a suitable implement (not shown) to 70 facilitate swinging of the heel portion relative to the toe portion in the use of the last.

To swingingly connect the toe and heel portions together I employ a peculiarly formed plate 22. This plate is rigidly secured in the socket 14 of the heel portion by means of suitable fastenings 23, and it has curved slots 24 and 25 arranged concentric with the curve 17, and which slots slidably embrace pins 26 and 27 respectively, whereby 80 the swinging plate, when swung by the heel portion 11, moves in an arc parallel with the arc of the curvature 17. This plate 22 is pivoted in ears 28 of the sleeve 29, slidably mounted in an extension 30 of the aforesaid 85 socket 15 in the toe portion. This sleeve has an internal annular shoulder 31, against which and the inner end of said socket extension 30 bears a spring 32, which provides for a yieldable mounting of the sleeve 28 in 90 the socket extension 30. A link 33 is pivoted at 34 to the short nose portion 35 of the plate 22, and at its opposite end the link 33 is pivotally mounted at 36 in the socket 16 of the expandable and contractible extension 95 13 of the toe portion. When the toe and heel portions are expanded, as shown in Fig. 1, and which is the position of these parts when the last is used to last or relast a shoe, the spring 32 forces the sleeve 28 toward the heel portion of the last. In this position of the parts, the link connection 33 between the plate 22 and the expandable and contractible extension 13 throws said extension away 100 from the body of the toe portion to its expanded position, the outward expansion of the extension 13, or course, being limited by the length of the link 33.

105 From the foregoing it will be seen that I provide a simple, inexpensive, durable, and 110

efficient device, particularly serviceable for relasting purposes, but it will be understood that the improvement is equally applicable for ordinary lasting purposes.

5. What is claimed is:—

- A last including a toe portion, a heel portion, the toe portion having an expandible and contractible section, said toe and heel portions meeting upon a curve, a plate fixed 10 to the heel portion and entering a recess formed in the toe portion, said plate being formed with arcuate slots, pins carried by the toe portion and extending through said slots, the edge of said plate which is disposed 15 within the recess of the toe portion being formed with spaced apertured projections, one of said projections being disposed at substantially the center of the plate and the other at the upper edge of the plate, a link 20 connecting the last mentioned projection

with the expandible section of the toe portion, a barrel, one terminal of which is bifurcated, said barrel extending within the toe portion, the projection arranged substantially centrally of the plate extending between 25 the bifurcations of said barrel, a pivot pin passing through said bifurcations and said extensions and a spring housed by the barrel and contacting with the same, said spring exerting pressure on said plate through the 30 medium of the barrel to maintain the heel and toe portions in their extended position and the expandible section of the toe portion in its expanded position.

In testimony whereof I affix my signature 35 in presence of two witnesses.

PATRICK H. HICKMAN.
